UNITED STATES PATENT OFFICE

91,313

DESIGN FOR A COMBINED OIL BURNING HEATER AND COOK STOVE

William T. Bradbury, Kankakee, Ill., assignor to
Florence Stove Company, Gardner, Mass., a
corporation of Massachusetts

Application November 1, 1933. Serial No. 49,625

Term of patent 7 years

To all whom it may concern.

Be it known that I, WILLIAM T. BRADBURY, a citizen of the United States, residing at Kankakee, in the county of Kankakee and State of Illinois, have invented a new, original, and ornamental Design for a Combined Oil Burning Heater and Cook Stove, of which the following is a specification, reference being had to the accompanying drawing, forming part thereof.

Figures 1 and 2 are perspective views of a com-

bined oil burning heater and cook stove showing my new design, and comprising a cabinet having a top which is shown in Fig. 2 as swung into an open position to expose a cooking top.

I claim:

The ornamental design for a combined oil burning heater and cook stove substantially as shown and described.

WILLIAM T. BRADBURY.
